UNITED STATES PATENT OFFICE

147,363

DESIGN FOR A TOBACCO SMOKING PIPE

Frank J. Danilowicz, Cleveland, Ohio

Application March 12, 1946, Serial No. 127,398

Term of patent 14 years

(Cl. D85—8)

To all whom it may concern:

Be it known that I, Frank J. Danilowicz, a citizen of the United States of America, residing at Cleveland, county of Cuyahoga, and State of Ohio, have invented a new, original, and ornamental Design for a Tobacco Smoking Pipe, of which the following is a specification, reference being had to the accompanying drawing, forming a part thereof, wherein:

I claim:

The ornamental design for a tobacco smoking pipe, as shown.

FRANK J. DANILOWICZ.
